UNITED STATES PATENT OFFICE.

PETER MALMSTRÖM AND PAUL E. DUMMER, OF NEW YORK, N. Y.

IMPROVEMENT IN BOTTLE-STOPPERS.

Specification forming part of Letters Patent No. 123,920, dated February 20, 1872.

To all whom it may concern:

Be it known that we PETER E. MALMSTRÖM and PAUL E. DUMMER, both of the city, county, and State of New York, have invented a new and useful Improvement in Bottle-Stoppers; and we do hereby declare the following to be a full, clear, and exact description thereof, which will enable those skilled in the art to make and use the same, reference being had to the accompanying drawing forming part of this specification, in which drawing—

Figure 1 represents a vertical central section of this invention. Fig. 2 is a side view of the same.

Similar letters indicate corresponding parts.

This invention consists in forming a recess in the top edge of a bottle, into which is fitted the ends of an arched bridge-plate, said bridge-plate forming the guide for the valve-stem and a support for the reacting spring, all of which will now be set forth in detail.

In the drawing, the letter A designates a bottle, the mouth B of which is provided with a recess, a, near its outer end, forming a seat for a segmental bridge, E, which forms a guide for a stem, b, of a valve, D, on which is arranged a coiled-wire spring, C, so that by the action of said spring the valve is pressed up against the inner edge of the mouth B. The valve is composed of the metallic body c, which is just large enough to pass in through the mouth B, and which is provided with a circular groove, d, for the reception of a disk, e, of India rubber or other suitable material. If the bottle is filled with an effervescent liquid, such as carbonic-acid water, the internal pressure forces the valve partly up into the mouth B, and, as the disk e becomes wedged in between the large end of the body c and the inner sur-

face of the mouth, a tight joint is produced, which prevents the discharge of any part of the contents of the bottle; but if it is desired to pour out a portion or the whole of said contents, the outer end of the stem b is pressed inward, which causes the valve to open, and the liquid is free to discharge from the bottle.

The bridge E being semispherical, and being placed on the outer edge of the neck of the bottle, does not materially obstruct the flow of the liquid from the same, and the spring C being placed above and bearing on said bridge serves to retain the same in position. The bridge E, being received in the recess a, does not interfere with the operation of filling the bottle in the ordinary bottling machine, and at the same time the valve can be easily held open by pressing with the finger on the end of the stem.

I do not broadly claim a valve which closes up against the inner surface of the mouth of a bottle by means of a spring arranged upon the valve-stem, said stem being guided in a bridge piece, the edges of which extend over the top of the bottle; but

What I claim as new, and desire to secure by Letters Patent, is—

An improved bottle-stopper, composed of the bridge E, secured in an annular recess, a, stem b, spring C, and valve e, all combined and arranged as herein shown and described.

This specification signed by me this 29th day of December, 1871.

PETER E. MALMSTRÖM.
PAUL E. DUMMER.
